LUMBIA.

TYPE-CLAMP.

1,113,249.

Specification of Letters Patent.

Patented Oct. 13, 1914.

Application filed July 30, 1913. Serial No. 782,019.

To all whom it may concern:

Be it known that I, GOLDEN RULE, a citizen of the United States, residing at Washington, in the District of Columbia, have invented certain new and useful Improvements 5 in Type-Clamps, of which the following is a specification.

This invention relates to type clamps and has for its primary object to provide a device 10 vice of this character which will automatically adjust itself to various sizes of type pages after the same have been set up into form.

Another object of the invention resides in 15 the provision of a simple and efficient device which will facilitate the handling of type pages and will reduce the expenditure of time of make up and imposition of each page to a minimum.

Other objects as well as the nature, characteristic features and scope of my invention 20 will be more readily understood from the following description taken in connection with the accompanying drawings and pointed out in the claim forming a part of this specification.

Referring to the drawings:—Figure 1 is a side elevation of the device constructed in accordance with my invention; Fig. 2 is a plan view of the same; Fig. 3 is a side elevation showing the complementary side arms in an expanded position; Fig. 4 is a detail perspective fragmentary view of one of the complementary side arms and a perspective 35 sectional view of a portion of the opposite arm; Fig. 5 is a top plan view of a galley illustrating the application of my improved angle-bar; and Fig. 6 is a detail perspective view of the angle-bar.

In the drawings wherein is illustrated the preferred embodiment of this invention a rectangular frame is provided which comprises a plurality of complementary arms 6 each one of which is provided with an elongated 40 tongue 7 integrally formed therewith and a split tongue 8 arranged in parallelism to the tongue 7. The tongue 7 is so formed as to provide an elongated shoulder 9 on which the ends of the split tongue 8 rest 45 while the inner ends of the split tongue 8 are so formed as to provide an elongated channel 10 which is slidably engaged with the extreme end of the tongue 7. Each side of the rectangular frame comprises a pair of

the arms 6 while the ends likewise comprise 55 a pair of arms, one of the side arms and one of the end arms being integrally formed, the one being turned at right-angles to the other as advantageously illustrated in Fig. 3 of the drawings. Upon application to this figure 60 it will be seen that of the two arms which form each side or end of the device, one arm has a split tongue 8 on top and a tongue 7 directly beneath, while the other arm has the tongue 7 on top and the split tongue 8 directly beneath; thus it is obvious that the arms may be slidably engaged with each other for performing the desired function. This disposition of the tongues 7 and 8 permits 65 minute adjustment of the frame both laterally and longitudinally as the tongue 7 is disposed for sliding engagement with the split tongue 8, the shoulder 9 in one instance supporting the said split tongue while the channel 10 in the other instance acts as a 70 support for the tongue 7.

In order to automatically adjust the arms to conform to the size of the type page a coil spring 11 is provided, one of which is arranged between each pair of the tongues 7 and 8, the opposite ends thereof having engagement in the eyelets 12, said eyelets being formed at the inner end of each of said side and end tongues. The object which is placed within the rectangular frame, in the present instance being a page 80 form of type is securely held in place in view of the fact that the frame is adjustable both in a longitudinal and lateral direction so as to snugly engage the sides of 85 the type form for facilitating the handling of the same.

In order to facilitate the clamping of the type after the same has been assembled in the galley, I have provided an angle-bar 13 which is of a size conforming to that of the ordinary galley, and is placed therein so that the outer face of each of the arms will engage with the inner face of one of the galley sides and ends as shown to advantage 90 in Fig. 5. The one end of the elongated arm 14 of the bar is preferably tapered as indicated at 15 for a purpose more fully hereinafter set forth.

In operation the type is set in the galley 105 in the ordinary manner after which operation the angle-bar 13 is placed therein so as to simultaneously move all the type ele-

ments or page form from engagement with the side and end of the galley with which it is in engagement, as it is well known in this art, that the type while being set is engaged with only one of the sides and the ends. My improved rectangular frame is then expanded so as to be readily engaged over the type form, the inner face of the side arms engaging with the sides of the form while the inner face of the end arms engages with the opposite ends of the form. The gripping of the form by the rectangular frame or type clamp is facilitated in view of the fact that the side arms on the one side of the frame can be engaged with the inner face of one of the sides of the galley with which the type is not in contact, while the other side and one of the ends of the frame is engaged with the angle-bar 13, the end 15 of the elongated arm being tapered in order to facilitate the fitting of the clamp over the type form.

It will be understood that the above description and accompanying drawings comprehend only the general and preferred embodiment of my invention and that various minor changes in details of constructions, proportion and arrangement of the parts may be made within the scope of the ap-

pended claim and without sacrificing any of the advantages of my invention.

I claim:—

A clamp comprising corner sections having side and end arms each of the arms of each of said corner sections being provided with a longitudinally-extending centrally-located slot forming one section of a spring seat, a finger extending from said arm above said slot, said arm having the sides of its upper portion cut away to form longitudinally-extending seats formed upon opposite sides of said finger to form a continuation of said finger above said slot, fingers extending from the lower portion of said arm beneath said first-mentioned finger and positioned in spaced relation to each other whereby the arms of said sections may be slidably connected, and resilient means positioned in the slots forming said spring seats and secured to said arms whereby said sections will be normally held in a contracted position.

In testimony whereof I affix my signature in presence of two witnesses.

GOLDEN RULE.
